UNITED STATES PATENT OFFICE.

ISAAC H. PEYTON, OF CENTRALIA, ILLINOIS.

RAIL-JOINT.

1,247,146.

Specification of Letters Patent. Patented Nov. 20, 1917.

Application filed March 30, 1916, Serial No. 87,868. Renewed May 28, 1917. Serial No. 171,573.

To all whom it may concern:

Be it known that I, ISAAC H. PEYTON, a citizen of the United States, residing at Centralia, in the county of Clinton and State of Illinois, have invented the new and useful Improvements in Rail-Joints, of which the following is a specification.

My present invention relates to improvements in rail joints, the primary object of 10 the invention being to provide a novel rail fastener for securing the abutting ends of rails, whereby the ends of said rails cannot become vertically or laterally displaced, and also preventing the sagging of the rail ends 15 at the joint.

Another object of this invention is to accomplish the above result by the provision of a device that can be quickly and easily installed, and which can be manufactured 20 economically and at a comparatively small cost.

With the above and other objects in view, the invention resides in the novel construction, combination and arrangement of parts, 25 which will be hereinafter specifically described, illustrated in the annexed drawings, and claimed in the appended claim.

In the accompanying drawings, wherein the preferred embodiment of my invention 30 is illustrated, like reference characters refer to like or corresponding parts throughout the several views.

Figure 1 is a perspective view of the rail joint of my invention. Fig. 2 is a vertical 35 sectional view through the same.

Referring now to the drawings, numerals 1 and 2 designate respectively, the meeting ends of two rails, a rail chair such as 3 supporting the ends of the joint. Chair 3 is 40 provided with an upturned flange on one side of the rail, preferably on the inner side, said flange being designated as 5, and being adapted to be bolted to the inner face of the rail. A space 4 between the rail and flange 45 5 is provided, in order to allow for the unevenness of the rail or chair.

On the opposite side of the rail joint I provide a fish plate 6 adapted to be bolted to the outer face of the rail, a space 4' being 50 also allowed between the rail and fish plate

for the purpose of adjustment. Bolts 8 are spaced on each side of the rail joint and pass through the fish plate, the rail, and the flange on the rail chair, nuts 9 holding the joint securely in the usual well known manner. Fish plate 6 is provided with extended feet 7 and the rail chair is provided with extended feet 3', which feet are adapted to be bolted together and to the tie by means of a rail-road spike 12. For this purpose, I provide feet 3' of the rail chair and feet 7 of the fish plate with square holes therethrough, which are designated respectively, by numerals 11 and 10. Square hole 10 is preferably spaced farther out from the edge 55 of the rail flange than hole 11, in order that spike 12 may engage the inner edge of hole 10, and thus force the fish plate against the rail.

I also provide rail chair 3 with spaced 60 apart lugs such as 13, and provide said lugs with vertical perforations 14 to admit a rail spike 15. The under face of chair 3 is provided with longitudinal sharpened ribs 16, which are adapted to seat securely in the 65 tie upon the application of weight to the rail.

From the foregoing description it will be readily seen that the rail joint of my invention provides simple and inexpensive means 70 of fastening the abutting ends of two rails, and that the device will effectively prevent sagging of the rails at the joint and the displacement of the rail either vertically or laterally.

While I have herein described and shown the preferred embodiment of my invention I do not wish to be limited strictly to the details shown as it is obvious that the construction and arrangement may be varied in 80 many ways, without departing from the broad spirit of my invention.

Having thus described my invention, what I claim is:

In a rail joint, the combination with the 85 meeting ends of two rails, of a rail chair supporting said rail ends, longitudinal sharpened ribs on the under face of said chair, lugs on said chair to receive railroad spikes, a fish plate on said rails, bolts uniting 90

85

100

the chair and fish plate to the rails, feet on the chair projecting from beneath the rail, feet on the fish plate positioned to rest upon the feet on the chair, and the feet of the 5 chair and fish plate having registering perforations adapted to receive railroad spikes therethrough, the inner wall of the perforation in the fish plate and the outer wall of

the perforation in the chair being positioned to be engaged by the spike to force the chair 10 and fish plate together against the rail.

ISAAC H. PEYTON.
